FLUSH PULL SLIDER FOR SLIDE FASTENERS

Frederick Ulrich, Bayonne, N. J., assignor to Com-
mar Products Corporation, Bayonne, N. J., a
corporation of New Jersey

Application April 29, 1941, Serial No. 390,905

11 Claims. (Cl. 24—205)

This invention relates to slide fasteners, and more particularly to sliders therefor.

A conventional slider for a slide fastener has a pull or finger piece pivotally mounted on top of the slider. The slider body is usually provided with an upstanding lug or projection on which the pull is pivoted. For some purposes, this construction is objectionable. When the fastener is used on a garment having a cloth flap overlying the same, the lug raises the cloth noticeably, and what is even worse, mars and may even tear through the cloth when the garment is treated under heavy pressure, as when ironing the same.

In an effort to overcome this difficulty, it has been suggested to use a flush pull, said pull extending all around the slider. This construction, however, introduces disadvantages of its own, because it widens the over-all width of the slider; it makes it difficult to stitch the tapes of the slide fastener to the garment by lines of stitching located as closely to the fastener elements as is desired; and it becomes impossible to provide the pull with a practical form of locking cam or locking tooth.

The object of the present invention is to provide a flush pull slider which will overcome the foregoing difficulties and disadvantages.

To the accomplishment of the foregoing general object, and such other more specific objects as will hereinafter appear, my invention consists in the slider elements and their relation one to the other, as hereinafter are more particularly described in the specification and sought to be defined in the claims. The specification is accompanied by a drawing, in which:

Fig. 1 shows a slider construction embodying features of my invention;

Fig. 2 is a side elevation of the slider;

Fig. 3 is a section taken approximately in the plane of the line 3—3 of Fig. 1;

Fig. 4 shows the lower end of a modified slider;

Fig. 5 shows the upper end of a modified pull, looking at the underside;

Fig. 6 shows the assembly of modified slider and pull;

Fig. 7 is a side elevation of the same;

Fig. 8 is a modification using a pin lock; and Fig. 9 shows the under side of the pull used in Fig. 8.

Referring to the drawing, and more particularly to Figs. 1, 2 and 3, the slider comprises a downwardly flanged top wall 12 and an upwardly flanged bottom wall 14 joined together at a neck portion 16. In the particular slider body

here shown, the neck portions are indented, and are secured together by welding, but other conventional slider constructions may equally well be employed.

The characteristic feature of the present slider is that the top wall 12 is smooth and flat, there being no upwardly projecting lug for the finger piece or pull. Instead, the pull 18 is disposed below and substantially flush with the top 5 of the slider. It is pivoted to the lower end of the slider, and so may be turned from the flat position shown at 18 in Fig. 2, to the transverse or broken-line position 18', preparatory to movement of the slider along the slide fastener. The fastener may be conventional, and as shown in Fig. 1, comprises tapes 20 provided with cords or beads 22 at their inner edges on which the fastener elements 24 are clamped. The lower end of the slider is only slightly wider than the width of the engaged fastener elements, and the pull 18 is preferably no wider than the lower end of the slider, and therefore is itself only slightly wider than the interlocked fastener elements, as will be seen at the bottom 10 of Fig. 1.

To secure the pull to the slider, the lower end of the top wall of the slider and the upper end of the pull are matingly cut away and interfitting when viewed in plan, the interfitting parts 20 being pivoted together on a transverse axis. Considering Figs. 1, 2 and 3 more specifically, the top wall of the slider is cut away at 26 and 28, thus leaving a downwardly projecting lug 30. The upper end of the pull 18 is notched 35 or cut away at 32 to fit around the lug 30. The parts or arms are secured together by a pin 34. The ends of the pin are exposed in Fig. 1 in order to clarify the construction, but in practice, these ends may, of course, be terminated 40 flush with the edges of the pull.

One important advantage of the present construction is the ease with which appropriate locking means may be provided. Thus, the spaced arms formed at the upper end of the pull may be coined or upset to form cams 36 which are adapted to bear tightly against the fastener elements when the pull is in flat position. It should be noted that the center of pressure of the cam is preferably offset from and is preferably 45 below the axis of pin 34, so that the device will be self-locking once the pull has been turned down. For the fastener to open, the slider must move relatively downward, or the fastener elements must move relatively upward, and any attempted relative movement of this kind tends 50

to swing the lower end of the pull downwardly or against the fastener. It may also be mentioned that the locking action is improved or tightened because one of the cams will bear directly on a fastener element when the other moves between elements, this being due to the staggered relation of the elements. Finally, it may be observed that the cams 36 shown in Figs. 1, 2 and 3 are particularly blunt, so that the lock will in this particular case act as a friction lock which will yield under an excessive or emergency pull on the slide fastener, without injuring the fastener. The present arrangement is particularly good for a friction lock, because the location of the cams so far below the neck 16 permits of a slight yieldability or spread of the slider when the slider is forced down while locked, as by forcibly pulling the garment open.

A modified construction is shown in Figs. 4 through 7 of the drawing. As before, the slider is provided with a top wall 40 and a bottom wall 42 joined at a neck portion 44, and the lower end of top wall 40 is provided with a downwardly extending lug or projection 46, located in the plane of the wall. The pull 48 is bifurcated to form arms 50, each of which carries an inwardly directed trunnion 52 formed integrally therewith. These arms are preliminarily spread to the diverging position shown in Fig. 5. The side edges of the lug 46 are indented to form sockets or holes 54 dimensioned to receive the trunnions 52. In practice, the pull may be added to the slider by means of a suitable fixture or die which positions the spread arms 50 astride the lug 46, and then bends the arms toward one another to the parallel position shown in Fig. 6, thus forcing the trunnions 52 into the bearing holes in lug 46.

The modified slider shown in Figs. 4 through 7 differs in several other minor respects. One is that the lug 46 in this case is projected downwardly from the lower end of the slider, instead of being formed by cutting away a part of the top wall of the slider. Thus the working length of the flanges of the slider is the same at the top and bottom, whereas in the arrangement shown in Fig. 2, the flanges at the top of the slider are shorter than those at the bottom. Another difference which will be clear from inspection of Fig. 7, is that the locking cams 56 are made more acute, thus giving the slider a more positive locking action. As before, the high point of the cam is preferably located below the axis, so as to make the slider self-locking once the pull has been nearly or wholly turned down. The choice of cam shape, as between the flat cam of Fig. 2 and the steeper cam of Fig. 7, depends on whether the slider is to act as a friction lock or as a positive lock.

The flush pull slider of my invention may also be provided with a pin lock. This is shown in Figs. 8 and 9, in which the slider comprises flanged top and bottom walls 58 and 60 joined at a neck portion 62. As before, the top wall is flat, and is provided with a downwardly extending lug 64. The pull 66 is bifurcated to straddle the lug 64, and may be provided with integrally formed trunnions 68, all as previously described. One of the arms 66 of the pull is projected beyond the trunnion 68, and is transversely bent 70 to form a locking tooth 70. This locking tooth is dimensioned to fit between successive fastener elements, and so acts as a typical pin lock. It should be noted that with the pin type of lock, the pin is provided at only one side of the pull, 75

as a similar pin, if symmetrically located at the other side of the pull, would tend to close on top of an element instead of between elements. This, while entirely feasible with a cam-shaped lock of moderate radius, cannot be done with a real locking tooth or pin of substantial length.

It is believed that the construction and operation of my improved flush pull slider for slide fasteners, as well as the advantages thereof, will be apparent from the foregoing detailed description. The pull is flush with the slider, and both have a smooth, flat top surface. The pull is no wider than the narrowest part of the slider, and is substantially as narrow as the interlocked rows of elements. Thus no objectionable bumps will be caused on a garment using this slider, and no injury to the fabric will result during ironing. The tapes of the fastener may be stitched to the garment reasonably closely to the fastener elements. The slider may, if desired, be provided with locking means, and various forms of locking cams and teeth may be employed.

It will be understood that the variant features disclosed in the drawing are interchangeable with one another. Thus, trunnions formed integrally with the pull may be used with the relatively flat cams or friction-lock shown in Fig. 2, and may be used with the shortened top wall shown in Fig. 2. Similarly, the positive locking tooth or pin of Fig. 8 may be used with either the shortened top wall of Fig. 2, or the separate pivot pin of Fig. 2, or both. When a cam lock is employed, a single cam may, if desired, be used instead of a double cam, although I believe the latter preferable.

With a cam lock, it is preferable to back up the fastener elements by means of the back wall of the slider, as shown in Fig. 3. The back wall may be extended downwardly without side flanges, if desired. If the back wall is not extended downwardly, as shown in Fig. 7, then the cam 56 should be given a substantial rise, because the grip against opening will depend primarily on offsetting or kinking the stringers at the lower end of the slider. For this kind of locking action, it is also better to provide a nearly square corner at the point 43 instead of a bevelled edge as shown in Figs. 2 and 8.

If the back wall of the slider is not to be extended downwardly, then the hooked pin lock shown in Fig. 8 is the most satisfactory, as it tends to lock independently of the back wall, assuming, of course, that the locking pin is very near the lower end of the slider.

The flush pull arrangement of the slider may, of course, be used without any lock at all, it having advantages even for such purposes or applications as do not require the use of a lock. The advantage of having a flush pull and also, the advantage of having a locking slider with a flush pull are, of course, not limited to the particular shape and dimension of the pull shown, in which the pull has the same width as the lower end of the slider. When the slider is unconventionally shaped, the pull may be adapted to the shape of the lower end of such an unconventional slider, so as to give the slider a pleasing appearance. The upper end of the pull may, for this purpose, require a width either wider or narrower than the interlocked fastener elements, instead of substantially equaling the interlocked fastener elements, as here shown.

It will therefore be apparent that while I have shown and described my invention in several preferred forms, many changes and modifications

may be made in the structures disclosed, without departing from the spirit of the invention as sought to be defined in the following claims.

I claim:

1. A slider for a slide fastener, said slider comprising top and bottom walls, and a pull, said pull being disposed in alignment with the lower end of the top wall of the slider, whereby said slider and pull in combination have a flat top surface, the lower end of the top slider wall being cut away when viewed in plan, and the upper end of the pull being matingly cut away and interfitted with the cut-away lower end of the top slider wall when viewed in plan, the interfitted parts being pivoted together on a transverse axis so as to permit the pull to be turned from its flat position to a transverse working position, preparatory to movement of the slider.

2. A slider for a slide fastener, said slider comprising top and bottom walls having downwardly converging flanges and joined at their upper end by a neck portion, and a pull for operating said slider, said pull having a width approximately equaling the width of the lower end of the slider and being disposed in alignment with the lower end of the top wall of the slider, whereby said slider and pull in combination have a flat top surface, the lower end of the top slider wall and the upper end of the pull both being matingly cut away and interfitted when viewed in plan, the interfitted parts being pivoted together on a transverse axis so as to permit the pull to be turned from a flat position substantially flush with the top of the slider to a transverse working position, preparatory to movement of the slider.

3. A slider for a slide fastener, said slider comprising top and bottom walls, and a pull, said pull being disposed in alignment with the lower end of the top wall of the slider, whereby said slider and pull in combination have a relatively flat top surface, the top slider wall being provided with a lug projecting from its lower end in the plane of the wall, said lug being substantially narrower than the slider wall, the upper end of the pull being bifurcated to form arms dimensioned to straddle the aforesaid lug, said arms having trunnions formed integrally with and projecting inwardly therefrom, said lug having bearing holes in the side edges thereof receiving the aforesaid trunnions, whereby said pull may be turned from a flat position substantially flush with the top of the slider to a transverse working position, preparatory to movement of the slider.

4. A slider for a slide fastener, said slider comprising top and bottom walls having downwardly converging flanges and joined at their upper end by a neck portion, and a pull for operating said slider, said pull having a width approximately equaling the width of the lower end of the slider and being disposed in alignment with the lower end of the top wall of the slider, whereby said slider and pull in combination have a relatively flat approximately flush top surface, the lower end of the top slider wall being notched or cut away at the sides to form a projecting lug, the upper end of the pull being slotted to form arms dimensioned to straddle the aforesaid lug, said arms having trunnions formed integrally with and projecting inwardly therefrom, said lug having bearing holes in the side edges thereof receiving the aforesaid trunnions, whereby said pull may be turned from a flat position substantially flush with the top of the slider to a transverse working position, preparatory to movement of the slider.

working position, preparatory to movement of the slider.

5. A locking slider made in accordance with claim 1, in which the upper end of the pull immediately adjacent the transverse pivot is provided with locking means dimensioned to engage the fastener elements when the pull is in flat position, but disengaged from the fastener elements when the pull is turned to transverse position.

10 6. A locking slider made in accordance with claim 1, in which the upper end of the pull is provided with locking means dimensioned to engage the fastener elements when the pull is in flat position, but disengaged from the fastener elements when the pull is turned to transverse position, said locking means comprising one or more cam-like projections located at the upper end of the pull immediately adjacent the transverse pivot.

20 7. A locking slider made in accordance with claim 1, in which the upper end of the pull is provided with locking means dimensioned to engage the fastener elements when the pull is in flat position, but disengaged from the fastener elements when the pull is turned to transverse position, said locking means comprising a locking tooth or pin located at the upper end of the pull immediately adjacent the transverse pivot.

8. A locking slider made in accordance with claim 3, in which the upper end of the pull immediately adjacent the transverse pivot is provided with locking means to engage the fastener elements of a slide fastener when the pull is in flat position, but disengaged from the fastener elements when the pull is turned to transverse position.

30 9. A locking slider made in accordance with claim 3, in which the upper end of the pull immediately adjacent the transverse pivot is provided with locking means to engage the fastener elements of a slide fastener when the pull is in flat position, but disengaged from the fastener elements when the pull is turned to transverse position, said locking means comprising one or more cam-like projections formed integrally with and projecting from the arms of the pull.

40 10. A locking slider made in accordance with claim 3, in which the upper end of the pull immediately adjacent the transverse pivot is provided with locking means to engage the fastener elements of a slide fastener when the pull is in flat position, but disengaged from the fastener elements when the pull is turned to transverse position, said locking means comprising a locking tooth or pin formed integrally with and projecting downwardly from the lower face of one arm of the pull.

50 11. A slider for a slide fastener, said slider comprising top and bottom walls, and a pull, said pull being disposed in alignment with the lower end of the top wall of the slider, whereby said slider and pull in combination have a relatively flat top surface, the top slider wall being provided with a lug projecting from its lower end in the plane of the wall, said lug being substantially narrower than the slider wall, the upper end of the pull being bifurcated to form arms dimensioned to straddle the aforesaid lug, and means pivoting the arms to the lug, whereby said pull may be turned from a flat position substantially flush with the top of the slider to a transverse working position, preparatory to movement of the slider.

FREDERICK ULRICH.
